JAMES BLAKE AND EMIL F. BEGIEBING, OF UNION HILL, NEW JERSEY.

HOSE BRIDGE AND TOWER.

SPECIFICATION forming part of Letters Patent No. 531,091, dated December 18, 1894.

Application filed May 19, 1894. Serial No. 511,832. (No model.)

To all whom it may concern:

Be it known that we, JAMES BLAKE and EMIL F. BEGIEBING, both of Union Hill, in the county of Hudson and State of New Jersey, have invented a new and Improved Hose Bridge and Tower, of which the following is a full, clear, and exact description.

Our invention relates to improvements in that class of devices which are used by fire departments in extinguishing fires; and the object of our invention is to produce a comparatively simple and efficient apparatus which may be collapsed and folded into a comparatively small compass or extended and raised to the necessary distance, which is provided with a hose bridge adapted to carry lines of hose over a track or other obstruction, which has the bridge portion extensible to enable it to carry the hose to a comparatively great length, which is provided with means for discharging water without the use of the hose from the bridge, thus enabling it to be used as a fire tower, which has a revoluble nozzle operated from the truck and arranged so as to discharge water in any desired direction, which is provided with a convenient and simple arrangement of braces, which has all its parts arranged so as to be longitudinally extensible, and which is mounted on a truck so that the whole affair may be turned to any necessary position and very easily operated.

To these ends our invention consists of certain features of construction and combinations of parts, which will be hereinafter described and claimed.

Reference is to be had to the accompanying drawings, forming a part of this specification, in which similar figures of reference indicate corresponding parts in all the views.

Figure 1 is a broken end elevation of the tower with the upper part in section on the line 1—1 of Fig. 4, and with the tower and hose bridge in a partially extended position. Fig. 2 is a sectional plan on the lines 2—2 of Figs. 1 and 4. Fig. 3 is a broken side elevation of the apparatus in a folded position. Fig. 4 is a central vertical section of the tower and bridge. Fig. 5 is a sectional plan on the line 5—5 of Fig. 4; and Fig. 6 is a detail perspective view of one of the ladders used in connection with the apparatus.

The apparatus is mounted on a truck 10

which may be of any suitable construction and the truck carries a bed plate 11 on which is mounted a circular track 12, which is angular in cross section, as shown in Fig. 4, the track serving to support the rollers 13 on which is mounted the turn table 14 which carries the entire superstructure of the tower and turns in a casing 15 which is open at the top and 55 which is secured to the bed plate 11. The table has centrally on its under side a gear wheel 16, which is formed integral with the table and is driven by a horizontally rotating gear wheel 17, the latter being driven by a 60 pinion 18 on a shaft 19 which is held in suitable supports and is provided at one end with a crank 20, see Figs. 1 and 3, arranged within easy reach of the driver's seat, and it will be seen that by turning the crank 20 the connecting gearing turns the table 14 and thus 65 enables the whole apparatus on the table to be turned to the desired position.

The table 14 supports hangers 21 in which are journaled the trunnions 22 of the lower 70 or base section 23 of the tower, this section having an enlarged casing 23^a at its lower end which serves as a housing for the gear wheel at the foot of the tower. The trunnions 22 are provided with toothed segmental racks 75 24 which engage worms 25 on the shafts 26, which are mounted in suitable supports and have gear wheels 27 engaging a driving gear 28 which is provided with a crank handle 29, this handle being also arranged near the 80 driver's seat on the truck 10, as shown in Fig. 3, and by turning this crank it will be seen that the worms 25 are revolved and the segmental racks 24 actuated, and in this way the section 23 of the tower, together with the sections carried by it, may be raised to a vertical position or turned down into a horizontal position, as shown in Fig. 3.

The lower or base section of the tower, which tower is made up of a series of telescoping sections, has on opposite sides and in vertical rows anti-friction rollers 30 which serve as bearings for the second section 31 of the tower and enables this to be moved easily up and down within the section 23. The second section of the tower supports the third section 32 which is made up essentially of opposite plates 33 connected together in a suitable manner at the top and bottom, and this sec-

tion is operated as hereinafter described. It will be understood that the tower may be made of more than three telescoping sections, if desired, or with a less number of sections 5 without affecting the principle of the invention.

The second section 31 is moved by a screw 34 which is threaded to fit a hole in the thickened bottom 35 of the section 31, and the 10 screw is stepped in a suitable support 34^a and has a driving gear 36 at its lower end which is driven by a pinion 37 and crank 38, as illustrated in Fig. 1, and thus by turning the crank, the section 31 may be raised or lowered. The screw has a pointed upper end 39 to enable it to readily enter the section 32 of the tower, and to engage the racks 39^a on the said section 32 of the tower, and the screw thus serves to raise both sections 31 and 32; 15 the section 32 being raised until it leaves the screw and the section 31 being raised to the screw top.

In lowering, the section 31 moves down until the screw engages section 33, then both 20 move down together until the part 35 of section 31 passes off the thread at the lower end of the screw, and the continued rotation of the screw does not further affect section 31, but moves down section 33. In raising, the 25 tower section 33 moves first and lifts section 31 into engagement with the screw.

The upper section 32 of the tower is held from turning by lugs 41 in the section 31 between which the section 32 slides. The section 32 is held extended by the levers 42 which are curved to fit snugly against the sides of the section 31, see Figs. 1 and 2, and these levers have arms 43 attached, which arms project through slots 44 and 45 in the 30 sections 31 and 32 and thus hold the section 32 in a raised position.

The levers 42 are pivoted together, as shown at 46, see Fig. 2, and have outwardly-extending ends which enable the levers to be operated like a pair of shears and these ends are connected by a screw 47 which has a hand wheel 48 at the end by turning which the levers may be moved so as to force the arms 43 in or out as desired. The levers 42 have preferably a removable pivot pin 46 which is provided with a chain 49 to prevent it from being lost.

In raising the tower the arms 43 are placed in engagement with the section 32 before the 55 rack leaves the screw and then the lifting of the section 31 carries up the section 32 also. In lowering the tower the pins or arms 43 are not released from section 33 until rack 39^a engages the screw 34 and so there is no sudden drop.

The several sections of the tower have hooks 50 at their upper ends which are adapted to engage and support ladders 51, a series of which are carried on the truck to be 60 used in connection with the tower. The ladder 51 has broad feet 52 to enable it to stand

well, and at the top it is bent or curved slightly, as shown at 53, and terminates in a slotted plate 54 adapted to engage one of the hooks 50 and thus, by using a series of ladders, the tower may be easily climbed or the ladders may be extended from the tower to an adjacent building to enable firemen to enter the latter or to enable inmates of the building to escape.

At the upper end of the top section 32 are brackets 55 and 56, which support the bridge proper, the brackets 55 having the main portions 58 of the bridge fulcrumed to them and these portions of the bridge are of a trough-like structure, being concave on top and they are removably attached to the brackets 56, being connected by a pin 59 which is provided with a chain to prevent it from being lost.

By removing the pin 59 the bridge may be 85 swung on its fulcrum 57 so as to lie substantially parallel with the body of the tower, as shown clearly in Fig. 3.

Two sections 60 of the bridge may be pulled out, as illustrated in Fig. 1, so as to make the 90 bridge of any necessary length.

To prevent the bridge sections 60 from turning, their inner edges are doubled over, as shown at 61, so as to slide on the edges of the sections 58, as shown clearly in Fig. 4.

The bridge is provided on opposite sides with hand rails 62 which serve as guards to prevent people from falling off. The bridge is held rigidly in its horizontal position, when arranged for use, by braces 63 which are pivoted to ribs 64 on the under side of the bridge and which are hinged, as shown at 65 in Fig. 1, to enable the apparatus to be collapsed and folded. The braces are longitudinally extensible to provide for the varying height of 100 the tower, and each brace has at its lower end a clamping block 66 which is held on the longitudinally slotted base section 67 of the brace, this section being provided at the foot of the tower, as shown at 68, and the clamping block 110 is provided with a bolt 69 on which is a hand wheel 70 and thus, by manipulating the wheel, the block may be clamped firmly to the slotted section or loosened, and in this way the brace may be longitudinally adjusted. The 115 slotted sections 67 are connected with the lower section 23 of the tower by bolts 71 and a turn buckle 72, which may be adjusted so as to hold the slotted sections at the desired angle and give them the necessary strength.

It will be seen that a line or lines of hose may be laid over the bridge so as to be extended above the track and permit cars to pass beneath, but the apparatus serves also as a water tower and is provided with pipes 125 73 which extend longitudinally through the tower sections and have nipples 73^a at their lower ends to which hose may be attached. The pipes 73 telescope so as not to interfere with the movement of the tower sections, but 130 this feature is not illustrated in detail, as there is nothing novel about telescoping pipes.

The pipes 73 connect at the top with a cross pipe or T 74, which is provided with a nipple 74^a, so that if desired a hose may be attached to it, and it connects by a pipe 75 with a head 76 like an ordinary universal joint which permits it to turn freely, the head having a bent nozzle 77 which is adapted to discharge water upon the fire and to which a line of hose may be connected if desired. The head 76 is mounted on a shaft 78 which turns in suitable bearings and has, at its lower end, a beveled pinion 79 which meshes with a pinion 80 on a shaft 81 which is longitudinally extensible, as shown in Fig. 1, and is hung on the under side of the bridge, the shaft having at its inner end a pinion 83 adapted to mesh with a pinion 84 on the longitudinally adjustable shaft comprising the sections 85, 86 and 87 which turn in bearings 88 and are parallel with the tower sections 23, 31 and 32, the extensible shaft having at its lower end a hand wheel 89 by which it may be turned, and thus by turning this wheel the extensible shaft, the shaft 81, and the upright shaft 78 are turned so that the nozzle 77 may be pointed in any desired direction so as to discharge the water effectively.

It will be seen that when the tower is collapsed and laid in a horizontal position, the pin 59 may be removed, the bridge collapsed and folded above the tower, and the shafts separated, as shown clearly in Fig. 3, the whole affair being reduced to a compact shape. It will also be seen that by properly manipulating the several cranks, the tower may be quickly raised and turned to a desired position, while the ladders 51 may be easily adjusted, and the apparatus thus serves as a hose bridge, a water tower and a fire escape.

Having thus described our invention, we claim as new and desire to secure by Letters Patent—

1. The combination with the tower sections, the bottom of the second section having a threaded aperture and the section thereabove having internal racks, of a vertical screw extending up through the lower section and said threaded aperture into engagement with said internal racks and an operating

mechanism geared to the lower end of the 50 screw.

2. The tower apparatus comprising the truck, the turn table mounted thereon and provided with an operating mechanism, standards on the turn table, a casing 23^a having 55 trunnions journaled on the standards and provided with an operating mechanism, a step 34^a, the extensible tower, the lower section 23 of which is mounted in the said casing a screw 34 mounted in said step and having an operating gearing, the second section 31 having a threaded aperture in its bottom through which said screw passes and the third section 32 having internal racks engaged by the upper end of the screw. 65

3. The combination, of the water tower, the hose bridge thereon, the movable nozzle on the hose bridge, water supply pipes carried by the tower and connected with the nozzle, and a shaft and gear mechanism for moving 70 the nozzle from the foot of the tower, substantially as described.

4. The combination, with the tower, of the opposite brackets on the tower top, and the hose bridge hinged to one bracket and detachably connected with the other, substantially as described. 75

5. The combination, of the extensible tower, the folding hose bridge, the jointed braces, means for extending the braces longitudinally, and an adjustable connection between the braces and the lower portion of the tower, substantially as described. 80

6. The combination, of the telescoping tower sections having registering holes there-in, the levers pivoted on the outer section and provided with arms to enter the holes of the two sections, and the screw for adjusting the levers, substantially as described. 85

7. The combination, of the tower, the hooks 90 thereon, and the ladders having curved upper ends and slotted top plates, substantially as described.
